UNITED STATES PATENT OFFICE.

WILLIAM M. BELL, OF PORTSMOUTH, OHIO.

METHOD OF FORMING CLOSURES.

Application filed September 26, 1927. Serial No. 222,157.

This invention relates to a bung or sput for use in connection with steel drums, barrels or the like metal containers that require an opening for filling and removing the contents thereof.

The primary object of the invention is to provide a closure or sput and a simple and efficient method of constructing the closure or sput, the method being such that when carried out insures a fluid-tight connection between the closure and barrel in which the closure or sput is positioned.

Another important object of the invention is the provision of a sput which will permit of perfect drainage of the container and one which will not turn with respect to the container should it be found necessary to apply excessive force to the plug fitted in the closure or sput to remove the same.

20 A still further object of the invention is the provision of a sput wherein the plug used to close the sput will seat against the metal of which the body portion of the device is constructed.

25 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

35 Referring to the drawings:

Figure 1 is a vertical sectional view through dies in the act of forming a sput.

Figure 2 is a vertical sectional view through cooperating dies showing a step in the forming of the sput.

40 Figure 3 is a vertical sectional view through cooperating dies employed in completing the sput.

Figure 4 is a sectional view through a sput formed by the various steps described.

Figure 5 is a vertical sectional view illustrating the manner of punching the sput opening in the body of the container.

Figure 6 is a vertical sectional view through 60 coating die members employed in positioning the sput.

Figure 7 is a vertical sectional view showing a further step in the positioning of the sput in the container.

Figure 8 is a vertical sectional view through 65 coacting dies illustrating a still further step in the positioning of the sput.

Figure 9 is a vertical sectional view through 70 coacting dies illustrating the completing step in the positioning of a sput.

Figure 10 is a vertical sectional view through 75 a further modified form of sput.

Figure 11 is a vertical sectional view through 80 a further modified form of sput.

Figure 12 is another modified form of sput. 85

Figure 13 is a plan view of the preferred 90 form of sput.

Figure 14 is a fragmental sectional view 95 through a container showing the preferred form of sput as positioned.

Referring to the drawings in detail, the 100 reference character 5 designates the stationary die and the reference character 6 indicates the movable die employed in the construction of a sput.

The reference character 7 indicates a 105 length of suitable sheet metal of which the sput is formed which is positioned on the stationary die 5 in a manner as shown by Figure 1 of the drawings, the dies being provided with suitable cooperating extensions 8 and 9 respectively that move into openings or grooves in the die faces of opposed dies to bend and form the sput.

Spring pressed plungers 10 and 11 form 110 a part of the stationary die, which plungers move downwardly under the action of the movable die 6. The movable die is also provided with a spring pressed plunger 12 that acts to remove the disk 13 which is cut from the blank by the movable die after the movable die has been returned to its inoperative or uppermost position.

Dies 14 and 15 are provided in the completing step in the formation of the sput 115 and as shown, each of these dies is provided with an annular groove formed with curved walls conforming to the curvatures of the finished sput, and as shown, the unfinished sput as formed by the dies shown by Figure 2, 120 is inverted and placed in the die 15 in a manner as shown by Figure 3, whereupon the movable die 14 is moved downwardly into engagement with the upper end of the sput, with the result that the upper end of the sput 125 is bent inwardly as at 16, defining an annular groove or space for the reception of the flange of the container, which flange is formed in a

manner to be hereinafter more fully described.

The invention also embodies dies such as indicated at 17 and 18, the die 18 being provided with a cylindrical punching extremity 19 formed with a central opening to accommodate the extension 20 of the stationary punching die 17. Spring pressed plungers 21 are provided in the stationary die and move downwardly as the punching extremity 19 of the die 18 moves downwardly thereagainst. A spring pressed plunger 22 is provided in the die 18 for ejecting the portions 23 of the metallic container.

In the use of the punching die, the stationary section 17 thereof is positioned under the head or within the body of the container to which the sput is to be applied, and the movable die 18 is forced against the head or body portion of the container, which punches the opening in the head or container and at the same time bends portions of the head or container downwardly to define a flange 24.

The finished sput which is shown by Figure 4 of the drawings is now positioned in a stationary die 25 and the stationary die is positioned under the sput opening, the flange 24 being directed into the space between the inwardly bent end of the sput and the body portion thereof, whereupon the movable die 26 is brought into contact with the container head or body portion of the container adjacent to the flange, pressure being applied to force the flange 24 within the space as shown by Figures 7 and 8.

The dies 25 and 26 are now removed and the coating dies 27 and 28 respectively are brought into play adjacent to the sput with the result that the container head or container body is bent as at 29 so that the inner surface of the sput alines with the inner surface of the head or container, allowing the entire contents of the container to be drained therefrom, and eliminating the usual shoulder and flange adjacent to the sput that prevent complete drainage of the contents.

A modified form of sput is shown by Figure 10 in which the head or body of a container is shown as bent in a manner to secure the sput in position, the metal of the container forming a protector for the sput.

The sput in this form extends above the metal of the container as indicated at 30, where the sput is formed with external threads to receive the cap 31 which may be screwed in position to close the sput opening.

As shown by Figure 11, the sput 32 is formed with internal threads to receive the threads of the plug 33, there being provided a gasket 34 for further insuring a fluid-tight connection between the sput and plug or closure. It might be further stated that a sealer tab such as indicated at 35 may be positioned adjacent to the sput during the operation of positioning the sput in the con-

tainer, so that a sealing wire may be employed in connection with the closure, or plug 33.

The form of sput as shown by Figure 11 may be also positioned in a manner as shown by Figure 12, that is to say after the sput has been positioned, a suitable die may be employed for pressing that portion of the container or head in which the sput is positioned, outwardly as at 36 or to a point in a line with the outer edge of the sput.

When this form of the invention is employed, the plug which is indicated by the numeral 37 is provided with a substantially wide flange 38 which is of a width to close the space 39 that is formed during the bending operation.

The preferred form of sput however, is indicated by Figures 13 and 14, and it will be seen that this form of the invention is similar to that shown by Figure 10, except the sput 40 is provided with internal threads to accommodate the plug 41 which is also provided with a flange 42 that bears against the gasket 43 when the plug is properly positioned.

From the foregoing it will be obvious that due to the construction shown and described, the sput will be securely locked by the method carried out and will prevent twisting of the sput with respect to the head or container in which the sput is positioned should excessive pressure be exerted on the plug in an effort to remove the plug from the sput.

It will also be seen that due to this construction, the entire contents of a container or drum may be removed or drained therefrom, and that the plug used in connection with the sput will seat against the basic metal of which the container is formed, thereby insuring a fluid-tight connection.

I claim:

1. A method of forming a closure for sheet metal containers consisting in providing a ring member from a length of sheet metal, and simultaneously bending the circular member to define a short flange and a long flange, bending the long flange inwardly towards the short flange defining a flange receiving space presenting a curved inner surface, and finally threading the inner surface of the short flange.

2. A method of forming a closure for sheet metal containers consisting in pressing a length of sheet metal between coating dies to punch a circular body portion from the length of sheet metal, placing the circular body portion between cooperating dies to provide a body portion having spaced flanges of unequal lengths, and finally placing the body portion between coating dies to bend one of the flanges downwardly and inwardly, to define a double circular space.

3. A method of forming a closure for sheet metal containers consisting in placing a length of sheet metal between coating dies

and operating the dies to punch a ring member from the length of sheet metal, bending the ring member to define spaced flanges, placing the ring member in a die with the flanges 5 extended upwardly moving a die into engagement with one of the flanges to bend the same downwardly and inwardly to provide a curved double space to receive the flange of a bung opening, and finally threading the inner 10 surface of one of the flanges.

4. A method of forming a closure for sheet metal containers consisting in punching a body portion from a length of sheet metal and simultaneously bending the body portion to 15 define spaced flanges, bending one of the flanges along a curved line towards the other flange and providing a space to receive the

flange of a sput opening, and finally threading the inner surface of one of the flanges.

5. A method of forming a closure for sheet metal containers consisting in providing a ring member from a length of sheet metal and bending the ring member to define flanges, said flanges being in spaced relation with each other, bending one of the flanges 20 inwardly and downwardly towards the other flange to provide a space between the flange and main portion of the ring member to receive the flange of a sput opening, and finally threading the inner surface of one of the 25 flanges.

In testimony that I claim the foregoing as my own, I have hereto affixed my signature.

WILLIAM M. BELL.
